UNITED STATES PATENT OFFICE.

OSCAR L. INGRAM, OF WALLA WALLA, WASHINGTON, ASSIGNOR TO UNION TYPEWRITER COMPANY, OF JERSEY CITY, NEW JERSEY, A CORPORATION OF NEW JERSEY.

TYPE-WRITING MACHINE.

9,12,862.

Specification of Letters Patent. Patented Oct. 18, 1910.

Application filed January 16, 1908. Serial No. 411,115.

To all whom it may concern:

Be it known that I, OSCAR L. INGRAM, citizen of the United States, and resident of Walla Walla, in the county of Walla Walla and State of Washington, have invented certain new and useful Improvements in Type-Writing Machines, of which the following is a specification.

My invention relates to typewriting machines and more particularly to means for aiding in readily effecting erasures or corrections especially in the production of manifold work.

The main object of my invention is to provide simple and efficient means of the character specified.

A further object of my invention is to provide devices which are in the nature of attachments that may be readily substituted for those embodied in existing forms of typewriting machines without changing the structural features of said machines.

To the above and other ends which will hereinafter appear, my invention consists in the features of construction, arrangements of parts and combinations of devices to be hereinafter set forth and particularly pointed out in the appended claims.

In the drawings, Figure 1 is a fragmentary enlarged detail end elevation showing the upper portion of a No. 6 Remington typewriting machine with the devices of my invention applied thereto. Fig. 2 is an enlarged detail plan view of the paper table and its support with parts broken away. Fig. 3 is a longitudinal sectional view of the same taken on the line x-x of Fig. 1.

I have shown my invention embodied, in the present instance, in the No. 6 Remington machine to which the devices of my invention are readily adapted but it should be understood that the invention may be employed in various styles of typewriting machines.

The top plate 1 of the machine has upwardly extending risers 2 which support a guile rod 3 with which anti-friction rollers 4 coöperate, the rollers 4 being carried in the usual manner by a carriage truck 5, links 6 pivotally uniting a platen frame 7 to the truck. The platen frame carries a rotative platen 8 and is provided with a roller 9 at the front portion thereof which coöper-

ates with a shift rail 10. Upwardly projecting lugs 11 are formed on the carriage truck, each of said lugs being apertured for the reception of the supporting stems of a paper table. The parts thus far described are of the usual construction embodied in the No. 6 Remington machine and further detailed description thereof is deemed unnecessary.

A special form of paper table may be readily substituted for that ordinarily employed in the No. 6 Remington machine by removing the ordinary paper table from the hollow supporting lugs 11 and substituting the special form of paper table construction of my invention. This special paper table and its supporting means comprises a supporting frame 12 having downwardly extending spindles or projections 13 spaced apart according to the spacing of the lugs 11 and reduced at their lower ends 14 for reception in the openings in the lugs 11. These spindles 13 extend downwardly from an H-shaped metallic frame 15, the arms 16 of which extend fore and aft of the machine and are connected at 17 to cross bars 18 which likewise constitute part of the supporting frame. These cross bars are of a length which corresponds substantially to the length of the paper table and are provided with upwardly extending projections 19 and 20. The projections 20 constitute bearings for a pivot rod 21 which is received in openings in said projections and passes through corresponding openings in depending lugs 22 on the bottom of a plate-like paper table 23 at one end thereof so as to constitute a hinge or pivot on which the paper table may swing from the full line position shown in Fig. 3 to the position indicated in dotted lines in said figure where it is out of parallelism with the axis of the platen. The upwardly extending projections 19 constitute rests upon which the free end of the paper table is adapted to bear when the table is in the normal position and the projections 19 and 20 maintain the table above the body of the support so as to provide a space 24 between the support 12 of the paper table and the bottom of the paper table itself as clearly indicated in Fig. 3. This space extends substantially throughout the length of the paper table

and corresponds substantially to the length of the platen so that it is adapted to receive sheets of any width that may be received in the machine.

5 In the ordinary use of the machine the paper table will perform the function of the ordinary paper table, the sheets, as they extend from the platen, passing above the paper table. If, however, in the production 10 of manifold work, the operator desires to make an erasure, it is merely necessary to swing the paper table on its pivot, so all of the sheets below the particular sheet on which the erasure is to be made, may be placed beneath the paper table whereas the sheet on which the erasure is to be made extends above the paper table as shown in Fig. 1. In the present instance I have shown the first-copy sheet *a* extending above the paper 20 table, whereas the carbon copy sheet *b* and interposed carbon sheet *c* are shown beneath the paper table. An erasure having been made on the sheet *a* the sheets *a*, *b* and *c* may then be carried above the paper table 25 and the sheets *a* and *c* lifted or drawn forward to uncover the sheet *b* and the corresponding erasure may be made on the sheet *b* while it rests directly on the paper table. This last operation does not of course 30 differ from that which may be performed when the ordinary paper table is in use. In a like manner any number of sheets may be corrected without an impression being made through the carbon sheet or sheets in the 35 act of making the erasure.

While I have described one method of carrying out my invention it should be understood that various changes may be made without departing from the invention, 40 which contemplates broadly the provision of means which enable sheets in the machine to pass above and below the paper table in order that erasures may be made on one sheet while it rests upon the paper table 45 without causing any impression to be made through a carbon sheet or sheets on another sheet or on other sheets of paper while such erasure is being made.

From certain aspects of my present invention the part 23 may be considered as a combined paper table and erasing shelf, plate or bed operating as it does as an ordinary paper table to support the paper as it is fed to the platen and also as an erasing plate. From other aspects of the invention the part 23 may be regarded merely as an erasing plate since it possesses novelty as such whether or not it is used as a paper table.

60 What I claim as new and desire to secure by Letters Patent, is:—

1. In a typewriting machine, the combination of a platen, a paper table, the forward edge of which is at the rear of the platen, 65 and means which permit portions of sheets

in the machine to be transferred from above the paper table to a position below the paper table.

2. In a typewriting machine, the combination of a carriage, a rotative platen, a paper 70 table at the rear of the platen and which supports the paper as it is being fed forward to the platen for printing, and means which permit printed portions of sheets advanced beyond the platen to be arranged 75 part below the paper table and part on top of the paper table.

3. In a typewriting machine, the combination of a carriage, and an erasing plate movably mounted on the carriage to swing to a 80 position where certain of superposed sheets may be placed under the erasing plate and another of said sheets placed on top of said erasing plate.

4. In a typewriting machine, the combination of a carriage, a platen, and a paper table pivoted at one end only to said carriage and adapted to be swung laterally and longitudinally of the platen.

5. In a typewriting machine, the combination of a carriage, a rotative platen, and a laterally swinging paper table pivoted at one end only to the carriage and in rear of the platen so that sheets as they pass from the platen may be placed some above and 95 some below the paper table.

6. In a typewriting machine, the combination of a carriage, a platen carried thereby, a movable paper table comprising an erasing plate, and means whereby a space is provided 100 beneath the paper table to receive sheets which project from the platen.

7. In a typewriting machine, the combination of a carriage, a platen carried thereby, a movable paper table comprising an erasing 105 plate, and means whereby a space is provided beneath the paper table to receive sheets which project from the platen, said space being substantially coextensive with the length of the platen.

8. In a typewriting machine, the combination of a carriage, a hinged plate-like paper table, and a support on the carriage for said paper table, a space being formed between the paper table and support for the reception of one or more sheets.

9. In a typewriting machine, the combination of a carriage, a rotative platen carried by the carriage, a support carried by the carriage, a paper table hinged at one end to 120 said support in the rear of the platen to receive some sheets between said support and paper table and some sheets above the paper table.

10. In a typewriting machine, the combination of a carriage, a rotative platen carried by the carriage, a support carried by the carriage, a paper table hinged at one end to said support in the rear of the platen, 125 a space being formed between said support 130

- and paper table for the reception of one or more sheets which extend from the platen.
11. In a typewriting machine, the combination of a platen, a plate-like paper table and its support spaced apart and constructed and arranged to permit one or more sheets to be moved from above the paper table into the space beneath it after the sheets have left the platen.
12. In a typewriting machine, the combination of a carriage, a rotative platen carried by the carriage, a supporting frame carried by the carriage in the rear of the platen and having upwardly extending projections at the ends thereof, and a paper table pivoted at one end to the projections at one end of the supporting frame, said upwardly extending projections providing a space between the bottom of the paper table and of said supporting frame and in which space one or more sheets which extend from the platen may be received.
13. In a typewriting machine, the combination with a platen, of a plate-like support for the paper, said support being constructed and arranged to deliver the paper to the platen at the receiving side thereof to normally receive the paper on its upper surface as it is delivered from the platen, and means to permit the paper to be passed beneath said plate-like support.
14. In a typewriting machine, the combination with a platen, of a table-like support for the paper, said support being constructed and arranged to deliver the paper to the platen at the receiving side thereof to normally receive the paper on its upper surface as it is delivered from the platen and mounted to be swung up to an abnormal position to enable the written portion of the paper to be dropped freely beneath the position normally occupied by said table.
15. A paper supporting contrivance for typewriting machines comprising two supporting beds arranged one above the other in the rear of the platen, the upper bed comprising an erasing plate movably mounted relatively to the lower bed.
16. In combination with the carriage of a typewriting machine, a detachable paper supporting contrivance comprising parallel supporting beds for the paper, said supporting beds being mounted in the rear of the platen and one of which beds comprises an erasing plate mounted for movement relatively to the other.
17. In combination with the carriage of a typewriting machine, a detachable paper supporting contrivance comprising parallel supporting beds for the paper, said supporting beds being mounted in the rear of the platen, one of said beds comprising an erasing plate pivoted so that it may be swung to an abnormal position substantially at right angles to its normal position.
18. In a typewriting machine, the combination with a platen, of a plate-like paper table adapted to support a plurality of sheets as they are fed to the platen, and also to support printed portions of said sheets as they depart from the platen, and means whereby some of the said printed portions of the sheets may be placed beneath the paper table and some may be placed upon the paper table.
19. In a typewriting machine, the combination with a platen, of a paper table adapted to support a plurality of sheets as they are fed to the platen, and also adapted to support printed portions of said sheets as they emerge from the platen, and a sheet-support arranged beneath said paper table whereby certain of the sheets may be placed upon the underlying support and certain of the sheets upon the paper table.
20. In a typewriting machine, the combination with a platen, of two paper supports arranged one under the other, the upper paper support normally supporting a plurality of sheets as they are fed to the platen and as they are delivered from the platen, the under paper support being adapted to receive certain of the sheets when it is desired to make erasures upon the upper paper support.
21. In a typewriting machine, the combination of a carriage, a platen carried thereby, an erasing plate, and means whereby said erasing plate may be adjusted to permit placement of some of the sheets projecting from the platen under the said erasing plate and placement of some of said sheets upon the top of the said erasing plate.
22. In a typewriting machine, the combination of a carriage, a platen carried thereby, and an erasing plate which extends longitudinally of the platen and which is pivoted at one end so as to swing at its opposite end toward and away from the platen.
23. An erasing bed or plate for typewriters having attaching means for securing it substantially in alignment with the platen, said bed or plate being hinged at one end and adapted to be turned out of parallelism with the axis of the platen.

Signed at the borough of Manhattan, city of New York, in the county of New York, and State of New York, this 15th day of January, A. D. 1908.

OSCAR L. INGRAM.
